UNITED STATES PATENT OFFICE.

MICHAEL BURNS, OF EVANSVILLE, INDIANA, ASSIGNOR OF THREE-TENTHS TO SMITH WILTSIRE, THREE-TENTHS TO C. T. CURRY, AND ONE-TENTH TO FRANK ELMENDORF, ALL OF EVANSVILLE, INDIANA.

INDUCTANCE-REGULATOR FOR ALTERNATING-CURRENT CIRCUITS.

1,174,053.

Specification of Letters Patent.

Patented Mar. 7, 1916.

Application filed December 23, 1914. Serial No. 878,732.

To all whom it may concern:

Be it known that I, MICHAEL BURNS, a citizen of the United States, residing at Evansville, in the county of Vanderburg and State of Indiana, have invented certain new and useful Improvements in Inductance-Regulators for Alternating-Current Circuits; and I do hereby declare the following to be a full, clear, and exact description of the same, reference being had to the accompanying drawings, forming part of this specification, and to the figures and letters of reference marked thereon.

This invention relates to that type of current regulators which are specifically adapted for controlling the current flowing in alternating current circuits and is more especially designed for regulating the current used in connection with electric lights such as are employed in connection with motion picture apparatus, photographic printing apparatus, etc., etc., where the carbons are under the manual control of the attendant. In the handling of lights of this character it is found that the wattage consumed may be very considerably reduced by the employment of an inductance regulator in the circuit, without material reduction in the illumination, and, at the same time, by the provision of an inductance regulator which may be readily and accurately adjusted to suit the requirements for illumination at the particular moment, the control of the light is rendered much more efficient.

The present invention is designed to accomplish all of the objects hereinabove stated and to provide an exceedingly simple apparatus which may be put into the hands of the ordinary operator without danger of injury to the apparatus or to the operator himself through the careless handling or manipulation of the regulator or the parts associated therewith.

Referring to the accompanying drawings, Figure 1 is a side elevation of a regulator embodying the present invention, the near side of the housing having been removed. Fig. 2 is an elevation looking at the left hand end of the structure shown in Fig. 1, with the housing partly in section. Fig. 3 is a sectional elevation in a vertical plane longitudinally of the core. Fig. 4 is a top plan view partly broken away and

partly in section of the structure shown in Fig. 1. Fig. 5 is a detail section of the operating or adjusting lever showing the preferred means for electrically insulating the sections of the adjusting mechanism.

Like letters of reference in the several figures indicate the same parts.

In the particular embodiment of the invention illustrated, two coils A are provided having their terminals connected with binding posts a, a, whereby the coils may be included in the alternating current circuit, the arrangement of the coils being preferably in series with each other and in series with the light or lights to be regulated, although it will be understood that the coils may be otherwise connected with and included in the circuit in accordance with known practice, and that one or any desired number of coils may be employed.

To create the necessary inductance, a core is provided to form a magnetic circuit for the coil or coils, and in accordance with the present invention, this core is of laminated construction and is formed in sections hinged together at one end and adjustable toward and from each other at the opposite end whereby an air gap of regulatable width is provided for varying the inductance in the well known way. Conveniently the core is formed in two sections, one a fixed section B having fixed pole pieces B' extending through the coils A and a movable section C which for convenience may be termed an armature.

The section C or armature is connected to one of the pole pieces B' by a hinge connection and in order to reduce at this point as far as possible all magnetic resistance, the laminations of the pole piece and armature are sub-divided. The sections thus formed are overlapped in contact with each other as shown clearly in the drawings where the overlapping sections are indicated at B² and C², respectively, and the overlapping laminations are connected by a pintle or bolt D. The opposite pole piece and end of the armature are thus made capable of movement toward and from each other, whereby the air gap between them may be varied to vary the inductance of the controller.

In the preferred construction the arma-

ture C is made movable with relation to the pole piece and for effecting its movements, an operating lever is provided which is operatively connected with the pole piece and armature respectively and provided with an extended handle E with which the attendant may accurately control the relative movement of the parts so as to vary the width of the air gap with the greatest accuracy. As shown in the drawings, the lever, of which the handle E constitutes an extension, is in the form of a yoke, the two arms F and F' of which are pivotally connected with the armature at their lower ends, and while mechanically connected at their upper ends to form a rigid structure, they are electrically insulated from each other by interposed insulation f, and as shown in Fig. 5 this insulation f, preferably extends around a rib f', on one section of the yoke and is seated in a corresponding recess in the other section so as to make the parts rigid against relative movement. The two sections are drawn together by a screw or fastening device f'', beneath and around which suitable electrical insulating material f' is located so as to effectually prevent the formation of any electric current around any part of the core, due to the inductive action which is set up in the apparatus when in use. Links G are pivotally connected at their upper ends to the yoke and at their lower ends to the pole piece B', the arrangement being such that the lever and links form in effect a toggle lever arrangement which when the handle E is swung from one position to the other as indicated in full and dotted lines in Fig. 1, will cause the armature to be elevated or depressed with relation to the pole piece, and at the same time the magnetic pull on the armature will be resisted so that the parts may be held in adjusted position or moved against the magnetic pull with comparatively little effort on the part of the attendant.

To retain the parts in their adjusted position against all possible danger of accidental movement due to the magnetic pull on the armature, provision is made whereby the lever may be made to coöperate with a fixed toothed member, and this member is conveniently part of a casing adapted to inclose the armature and pole pieces so as to make the whole apparatus safe for handling or being located in proximity to other apparatus. The casing itself is supported on a frame preferably embodying mechanically connected, but electrically insulated plates H mounted above the coils A and held in proper fixed relation to the pole pieces by screws or fastenings h. The two plates H are insulated from each other at their ends by insulation i and are rigidly connected together by bridges I forming

the bases for the binding posts a. Side frames K (Fig. 2) extend upwardly from the casing frame H and at their upper ends support a sectional cover, the sections L and L' whereof are mechanically connected, but electrically insulated from each other by insulation l. The cover plates L, L' are preferably arc-shaped as shown in Figs. 1 and 3, a space being provided between their proximate edges for the movement of the control lever and handle E. The edge of one of said plates is toothed or serrated as shown at M in Fig. 4 for coöperation with a yielding projection m on the control lever, whereby the lever will be held in adjusted position, but at the same time may be readily moved by the attendant from one position to another as occasion requires.

In order to effectually insulate and separate the coils from the cores, the coils are preferably wound on a form around sectional liners N, there being suitable insulating material such as asbestos and asphaltum incorporated between the liners and windings, as well as between the windings themselves, and on the inner side of the linings, it being the design in the manufacture of the controller to position the parts accurately and fill all interspaces with asphaltum which is subsequently baked, so as to not only increase the rigidity and solidity of the structure, but to effectually prevent any short-circuiting between the several members.

By making the liners of the coils as well as the framing and operating lever mechanism sectional with insulating material located between the sections, no continuous path for the flow of induced electrical currents around the core and coils is formed and consequently the transformer action such as would otherwise be set up is effectually prevented, and consequently the parts will remain comparatively cool, inasmuch as the only heat generated will be that due to the resistance of the coils and magnetic currents set up in the coils. The latter are to a large extent eliminated by the provision of a laminated core wherein Foucault currents will not be created to any harmful extent.

In apparatus of this character a disagreeable humming is sometimes set up, and to eliminate this as far as possible, the corners of the armature and pole piece to which it is hinged are preferably cutaway or rounded as indicated at O in the drawings.

In the use of the apparatus it is a simple matter for the attendant to grasp the control handle E and to move the same for adjusting the width of the air gap so as to vary the magnetic inductance in accordance with the requirements of the light for the particular time desired. The convenience of the adjustment is of importance in apparatus of this kind, and it is essential that a close and

ready control of the light shall be instantly available to meet conditions of operation.

In actual practice, it is found that with the use of this inductance controller the wattage 5 consumption of current is materially reduced without reducing the illumination or efficiency of the light, so that it effects a material saving to the user, which is far greater than is possible by the use of rectifiers now

10 commonly employed.

What is claimed is:

1. An inductance regulator for alternating current circuits embodying a coil, a laminated core forming a magnetic circuit 15 through the coil, said core being formed in sections adjustable with relation to each other to vary the air gap between them, and an adjusting mechanism embodying a yoke, the arms of which are pivotally connected 20 at their lower ends with the armature and connected together at their upper ends, but electrically insulated from each other and links pivotally connected at their upper ends to the yoke and at their lower ends to the 25 pole piece.

2. An inductance regulator for alternating current circuits, embodying a sectional laminated core with the sections adjustable toward and from each other, a coil and 30 through which the core passes, a sectional housing frame surrounding and electrically insulated from the core and having its sections electrically insulated from each other, and a sectional closure carried by the frame 35 and having its sections insulated from each other.

3. An inductance regulator for alternat-

ing current circuits, embodying a coil, a sectional laminated core for the coil with the sections hinged together at one end, a lever 40 operatively connected with the other ends of the sections for adjusting said ends toward and from each other, and an operating handle on said lever whereby the wattage of the current traversing the coil may be 45 varied.

4. An inductance regulator for alternating current circuits embodying a coil, a sectional laminated core for the coil, means for adjusting the sections with relation to each other to vary the air gap, a casing formed of sections mechanically connected and electrically insulated from each other, an operating lever for the adjusting means projecting through the casing, and means for 55 retaining the lever in adjusted position.

5. An inductance regulator for alternating current circuits embodying a fixed core having upwardly projecting pole pieces, an armature hinged on one pole piece and projecting into proximity to the other pole piece, there being overlapping portions of the core and pole piece to which it is hinged in extended lateral contact with each other, and an operating lever for adjusting the position of the armature having arms embracing the armature, said arms being mechanically connected but electrically insulated from each other.
